GREASE FILTER

Anthony Jordan, 262 Great River Road,
Great River, N.Y. 11739

Filed Dec. 11, 1972, Ser. No. 313,767

Term of patent 14 years

Int. Cl. D23—04

U.S. Cl. D23—149

FIG. 1

FIG. 2

FIG. 3

FIG. 4

FIG. 1 is a top plan view of a grease filter showing my new design;

FIG. 2 is a front elevational view thereof;

FIG. 3 is a bottom plan view thereof; and

FIG. 4 is a right side elevational view thereof.

The left side and rear of the filter are identical to the right side and front respectively.

I claim:

The ornamental design for a grease filter, substantially as shown and described.
